CURTAIN ATTACHMENT DEVICE

George Frederick Beaumont and Cyril George Beaumont, West Bridgford, England

Application March 23, 1934, Serial No. 717,069
In Great Britain March 13, 1933

3 Claims. (Cl. 156—21)

This invention relates to improvements in curtain attachment devices which are employed for connecting curtains to the fixed rails or the like from which they are suspended, and it refers to 5 attachments of the kind which consists of two independent members, one of which is adapted to fit within the other with the curtain gripped between them. Its object is to provide a more convenient form of curtain attachment for the purpose described, than those at present available.

According to the present invention, a curtain attachment device consists of two independent members one the main part of which is formed with jaws or extensions thereon which enclose a 15 vertical space with a vertical opening at the front, through which a part of the curtain can be inserted and a peg or plug which is of about the same cross sectional shape and dimensions as and is adapted to fit in and occupy the whole of the 20 vertical space left between the jaws or extensions after the curtain has been inserted therein and thus secure the latter in the device.

In one construction one member may comprise 25 a peg with a lower end which is of the requisite size and shape to fit in the space left between the jaws of the other part after the curtain has been inserted therein.

Alternatively a short plug of the requisite size and shape to fit in the vertical space between the 30 jaws on the other part may be provided.

In some cases the main part with the attachment hook or ring may be formed with a part which constitutes a plug and the subsidiary 35 detachable member is formed with jaws or extensions to fit over the said plug.

It will be appreciated that the cross sectional shape of the space between the jaws and the peg or plug which fits therein, may be varied to a considerable extent without departing from the 40 invention.

The invention will now be more particularly described with reference to the accompanying drawing, in which

Fig. 1 is a front elevation, and

Fig. 2 a side elevation of a curtain hanger or attachment device constructed according to our invention.

Fig. 3 is a plan showing the main part without the subsidiary member.

Fig. 4 is a perspective view showing two of the hangers or attachment devices attached to a curtain.

Fig. 5 is a front elevation, and

Fig. 6 a side elevation showing a modification.

Fig. 7 is a plan showing the main part only of this modification.

Fig. 8 is a front elevation, and

Fig. 9 is a side elevation showing another modification.

Fig. 10 is a plan showing the main part only of this modification.

Fig. 11 is a front elevation, and

Fig. 12 a side elevation showing a further modification.

Fig. 13 is a plan showing the main part only of this modification.

Like letters indicate like parts throughout the drawing.

As shown in Figs. 1 to 4, our improved curtain hanger or attachment device comprises a main part A, with a hook F at the back and two curved jaws B at the front. These jaws B are disposed so as to provide a space between them into which a subsidiary member which may take 70 the form of a peg E of about the same cross sectional shape and size of the said space can be inserted. An opening C (see Fig. 3) is left at the front between the ends of the jaws B, and in attaching the hanger to a curtain, a part of the 75 latter D is passed through the opening C between the jaws B, and it is then secured to the hanger by subsequently inserting the peg E between the jaws with the curtain between the latter and the peg as shown in Fig. 4. Alternatively the curtain may be first placed partly round the peg E and both the curtain and peg be placed between the jaws B together. The peg E shown in Figs. 80 1 and 2 may be made of wood or other substance, and it will be seen that the curtain D is securely gripped between the exterior of this peg E round 85 which it passes and the interior of the space between the jaws B, as shown in Fig. 4, and that there is no risk of the hanger or attachment device becoming accidentally detached from the 90 curtain.

The hook F at the back of the main part A is as shown in Fig. 2, adapted to fit over a plain rail and slide along the same when the curtains are drawn. The main part A may however be 100 formed with hooks or various forms, or any other convenient means of attaching the said part to a curtain rail or runners thereon, or to the rings of curtain poles. In some cases the main part A of each hanger may be fitted with rollers so that 105 they will run freely along a rail.

It will be seen that when the device described is attached to a curtain, the main part A will be at the back, and the peg E at the front, and that at the point where each device is fixed, a slight 110

pleat is formed in the curtain. These pleats are not detrimental as they help the curtain to hang in a graceful manner.

In the construction shown in Figs. 5 to 7 inclusive, the jaws B on the main part A are adapted to receive a peg E which is circular in cross section, and in this case the jaws B may be formed so that the peg E and curtain may be sprung through the opening C between the free 10 ends of the said jaws.

In the construction shown in Figs. 8 to 10 inclusive, the main part A is formed with a plug G which is widest at the lower end and the subsidiary member H is formed with jaws or extensions which are adapted to fit over the plug G and thus embrace it. In this construction, a part 15 of the curtain is carried round the plug G, and then the member H is placed over that part of the curtain which is disposed round the said 20 part G.

If preferred, a wedge shaped metal member J, such as that shown in Figs. 11 to 12, may be used instead of a wooden or like peg. This member J is formed by bending a sheet metal blank into 25 a cross sectional shape that is adapted to fit into the space between the two jaws B.

In some cases the pegs E may be of such a length that they project upwards some distance above the jaws B, and serve to support in an upper 30 position that part of the curtain D that is above the line on which the holders or attachment devices are disposed.

The main part A of the curtain hanger shown in Figs. 11 to 13 is formed with a hook M at the 35 top, and this construction may be adopted with any of the different modifications described and shown.

The main parts of the curtain hanger can be most conveniently made from sheet metal blanks stamped into the requisite form, but it is obvious that they can be made of other classes of material.

The advantage of the curtain hangers or attachment devices described and shown, is, that they can be more readily attached to a curtain, than existing devices. 80

Having thus described our invention we claim:— 85

1. A curtain attachment device consisting of two members one of which is formed with jaws thereon which partially enclose a vertical space and leave a vertical opening at the front through which a part of a curtain can be inserted and the other consists of a plug of about the same cross sectional shape and dimensions as and is adapted to fit in the space between the jaws after the curtain has been inserted therein and thus secure the latter in the device, substantially as 90 described. 95

2. A curtain attachment device according to claim 1, in which one member is formed with jaws that provide a vertical space with a vertical opening at the front and the other member consists of a peg with a lower end of the requisite size and shape to fit in the space between the jaws 100 after the curtain has been inserted therein, substantially as described.

3. A curtain attachment device according to claim 1 in which the part which constitutes the plug is formed on the main part with an attachment hook and the subsidiary removable member is formed with jaws to fit over the said plug, substantially as described. 105
